(57) **CLAIM**

The ornamental design for a projection device, as shown and described.

DESCRIPTION

FIG. 1 is a front perspective view of a projection device according to the present invention.

FIG. 2 is a rear perspective view of FIG. 1.

FIG. 3 is a top view of FIG. 1.

FIG. 4 is a bottom view of FIG. 1.

FIG. 5 is a front view of FIG. 1.

FIG. 6 is a rear view of FIG. 1; and,

FIG. 7 is a left side view of FIG. 1.

The broken line(s) shown in the drawings are for illustrative purposes only and form no part of the claimed design.

The right side of the design is a mirror image of the left side, so the right view has been omitted.

The stippling and shading lines shown in the drawing(s) represent the approximate three-dimensional contour of the design, and are not intended to indicate surface decoration.
